DESIGN FOR A CHAIR PAD COVER

Moses Caplan, Boston, Mass.

Application March 9, 1938, Serial No. 75,697

Term of patent 3½ years

To all whom it may concern:

Be it known that I, Moses Caplan, a citizen of the United States, residing at Boston, in the county of Suffolk and State of Massachusetts, have invented a new, original, and ornamental Design for a Chair Pad Cover, of which the following is a specification, reference being had to the accompanying drawing, forming part thereof.

The single figure of the drawing is a plan view of the chair pad cover, showing my design.

I claim:

The ornamental design for a chair pad cover, substantially as shown.

MOSES CAPLAN.
